ANCHORING DEVICE FOR TRANSPORTABLE
HOISTING AND HAULING APPLIANCES

Franz Belt, Vienna, Austria

Application June 10, 1931, Serial No. 543,483,
and in Austria May 19, 1931

10 Claims. (Cl. 254—135)

This invention relates to a device for the mounting and anchoring of transportable hoisting and hauling appliances, and has for its principle to mount an appliance of the said order in such a manner as to be rotatable between a standing stirrup-shaped member and a ground support placed at right angles to the direction of pull, the said support together with a further ground support disposed parallel to the direction of pull being adapted through the use of means to be described hereafter to be secured to the ground in such a manner that the same is firmly anchored with respect to the direction of pull, but at the same time is easily detachable from the ground.

The requirements of such a device as the present invention sets out to provide, particularly for use in connection with hand winches or capstans for the lifting or salving of vehicles and for the hauling of the same over obstacles and steep places, or the like, are in the first place that it shall enable the lifting and hauling devices attached thereto to be adjusted and set in position with their axes of rotation in the desired relation to the direction of pull, and in the second place that it shall be able to anchor the said appliances in any natural or artificial ground conditions so effectually and reliably that the load can be hauled or lifted without danger of slipping or giving way. A further essential requirement is that, with a view to reducing the dead weight of the vehicle, the device must be light in weight and must be capable of being fixed in position and operated by one man (the driver of the vehicle alone).

The problem here presented has been solved by the present invention, since the device provided thereby is of extremely light weight, enables a reliable anchorage to be obtained in a simple and easy manner in any kind of ground, and enables the angular position of the winding drum axis to be set as desired in relation to the direction of pull.

An example of the carrying out of the invention is illustrated in the accompanying drawing, in which:—

Fig. 1 shows the device according to the invention, in perspective.

Fig. 2 shows a modified detail of the same, likewise in perspective.

The lifting or hauling appliance is for the sake of simplicity merely indicated in the drawing as a drum T which is to be taken as representing either a windlass drum, a capstan drum, or the effective drum of a whole set of drums or

rollers, since the particular arrangement and construction of the lifting or hauling appliance itself is immaterial to the present invention. The supporting of the lifting or hauling appliance T is effected by a ground support 1 disposed at 60 right angles to the direction of pull, on which support the axle 2 of the lifting or hauling appliance T is articulated so as to be tiltable about a bolt 3, while the upper end of the axle 2 is fitted in a stirrup-shaped member 4 which is likewise 65 tiltably mounted on the ground support 1 by means of bearing lugs 1' to which the stirrup 4 is attached for instance by means of bolts and nuts. In the middle of the ground support 1 there is provided a hinge joint 5 by means of 70 which a further ground support 6 disposed in the direction of pull can be articulated to the transverse supporting member 1. The longitudinal support 6 is provided at its rear end with a coupling member 7, in the form of a shackle, 75 eye, or the like, by means of which additional extension supports 6' of the same type as 6 can be connected as circumstances require. The pivoted stirrup 4 is provided in its upper part with a hinge 8 to which a back stay or support 9 80 is articulated for the purpose of enabling the angular adjustment of the axle 2 of the drum T in relation to the ground support 1 to be fixed. In order to obtain a reliable fixation of the back stay 9, in view of the very great pulling strains 85 to be dealt with, a clamping eccentric lever 10 is slidably attached to the longitudinal supporting member 6. To this end the clamping lever 10 is held to the support 6 by means of a band or stirrup 12 and an adjusting screw 13 passed 90 through the ends of this stirrup and through the eccentric pivot hole in the foot portion of the said lever. The slackening of the screw 13 enables the lever 10 to be slid longitudinally of the support 6. As will be clear from the drawing, 95 this construction causes the lever 10 to be more firmly clamped to the support 6 the greater is the pull exerted on the drum T, thus precluding the alteration of the setting of the back stay 9 through slip, irrespective of the weight of the 100 load. In order to further facilitate the adjustment of the angle of the drum axis, the back stay 9 is provided with a plurality of holes 9' to which the clamping lever 10 can be attached as required, for instance by means of a bolt or bolts 105 passed through both parts.

The anchoring of the supporting members 1 and 6 in the ground is effected by means of special peg shoes or lugs which are either rigidly connected to the supports (formed simultane- 110

ously therewith by swaging) or are arranged to be slidably adjustable thereon. In the example shown in the drawing, the support 1 has a peg shoe 14 of this type at each end, these shoes being provided with a hole 15 inclined at an angle to the vertical. Through these holes pegs P (nails, pins, bars, or the like) are either inserted or driven by means of a hammer or other suitable tool into the ground. The support 6 is likewise provided with similar lugs 16 which are also obliquely drilled to receive the described anchoring members P driven therethrough into the ground.

For the purpose of anchoring the supports into a street surface formed of blocks, a modified form of support 6a, as shown in Fig. 2, is employed on which the peg lugs 16a are adapted to be slidable in an axial direction and to be clamped in position by means of screws 18. These lugs are provided with vertical holes through which the pegs P can be driven into the crevices between the blocks, these pegs being held in position in the holes of the lugs 16a by means of set-screws 19.

By means of these special anchoring elements it becomes possible to anchor the hoisting or hauling appliance to any kind of ground met with under practical conditions. In the case of soft humus or marshy ground it merely becomes necessary to link together as many longitudinal supporting members 6, 6', etc. as possible with a view to enabling as large a number of pegs as possible to be employed. These pegs P can be driven by hand, and, in view of their oblique and cross-wise positions, grasp as large as possible a volume of the ground material, and thus provide a reliable anchoring of the hoisting or hauling appliance even for the heaviest loads. In the case of hard ground a single longitudinal support 6 is sufficient, the lugs 16 being anchored by means of pegs driven into the ground by hand, while in the case of road surfaces formed of stone or other blocks the method of anchoring illustrated in Fig. 2 is adopted, whereby the lugs can be adjusted longitudinally of the support to enable the pegs to be driven vertically into the crevices between the blocks. The adjustment of the angular position of the hoisting or hauling device is effected by the adjustment of the back stay 9 or of the clamping lever 10, after first tilting the stirrup 4 and therewith the drum T into the required position. Since the foundation for the device according to the invention is resolvable essentially into two bars (of round, T-shaped, or other cross-section), the device is of light weight, easily manipulated, and yet capable of providing a reliable anchorage for a pulling strain of any magnitude.

I claim:—

1. A device for the mounting and anchoring of transportable load lifting and hauling appliances comprising a bar-shaped supporting member at right angles to the direction of pull, a stirrup-shaped member attached to the upper side of the said support, means for carrying a lifting and hauling appliance between the said support and the said stirrup-shaped member, a second

bar-shaped supporting member attached at right angles to said first bar-shaped member, and means for anchoring the said bar-shaped members to the ground in such a manner as to be easily detachable yet rigid in the direction of pull.

2. A device according to claim 1, wherein the said stirrup-shaped member and the said carrying means are tiltably mounted upon the said first bar-shaped supporting member.

3. A device according to claim 1, wherein the said stirrup-shaped member and the said carrying means are tiltably mounted upon the said first bar-shaped supporting member, and further comprising means for adjusting and fixing the angular position of the said stirrup-shaped member and carrying means in relation to the direction of pull.

4. A device as claimed in claim 1, in combination with a back stay hinged to the upper rear portion of the said stirrup-shaped member, and a clamping eccentric lever adapted to be slidable and fixable upon the said second bar-shaped supporting member, and means for connecting the said back stay to the upper end of the said clamping eccentric lever.

5. A device according to claim 1, further comprising in combination with the said bar-shaped supporting members lugs attached to the said members, oblique holes in the said lugs, and pegs adapted to be driven through the said holes into the ground.

6. A device as claimed in claim 1, further comprising lugs slidably mounted upon the said supporting members, vertical holes in the said lugs, and pegs adapted to be driven through the said holes into the crevices between the blocks of an artificial ground surface.

7. A device as claimed in claim 1, further comprising a coupling member at the outer end of the said second bar-shaped supporting member, for the purpose of enabling a further supporting member similar to the said second supporting member to be detachably connected as an extension thereto.

8. A device as claimed in claim 1, in combination with a back stay hinged to the upper rear portion of said stirrup-shaped member, and a clamping eccentric lever adapted to be slidable and fixable upon the said second bar-shaped supporting member, and adjustable means for connecting the said back stay to the upper end of said clamping eccentric lever.

9. A device as claimed in claim 1 in combination with lugs rigidly attached to said bar-shaped supporting members, oblique holes in said lugs, and pegs adapted to be driven through the said holes into the ground.

10. A device as claimed in claim 1, in combination with lugs slidably mounted on said bar-shaped supporting members, means for fixing said lugs to said supporting members in any desired position, oblique holes in said lugs, and pegs adapted to be driven through said holes into the ground.

FRANZ BELT.
